(57) **CLAIM**

The ornamental design for mounting plate for flat panel displays, as shown and described.

DESCRIPTION

FIG. 1 is a front perspective view of our design for a mounting plate for flat panel displays.

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The broken lines shown on the drawings is included for the purpose of illustration and forms no part of the claimed design.
